UNITED STATES PATENT OFFICE.

HENRY N. JOHNSTON, OF BROCKPORT, NEW YORK.

HARVESTER.

SPECIFICATION forming part of Letters Patent No. 237,539, dated February 8, 1881.

Application filed April 12, 1880. (No model.)

To all whom it may concern:

Be it known that I, HENRY N. JOHNSTON, a citizen of the United States, residing at Brockport, in the county of Monroe and State of New York, have invented certain new and useful Improvements in Harvesters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in harvesters in which the grain is carried on a canvas belt to a platform, where it is bound by suitable binding mechanism.

The objects of my improvements are to provide means for carrying the grain to the binding-platform without the belt or band passing over the drive-wheel; and it consists in details of construction, that will be hereinafter more fully set forth in the specification and claims, and pointed out in the accompanying drawings, in which—

Figure I is a plan view of my machine; Fig. II, a rear elevation; Fig. III, an end elevation; Fig. IV, a detail view of the front or guide wheel and manner of attaching same; Fig. V, a detail view of the pawl and ratchet-wheel for raising and lowering one or both sides of the machine.

A is the main platform, supporting the cutter-bars D and carrying-belt C.

E is the drive-wheel, which is connected on one side to the driving-shaft F by a universal or toggle joint, e, its opposite side being connected by a rod, H, passing under the main platform and attached to the guide-wheel frame I. A bevel-gear wheel, G, on shaft F actuates a pinion-shaft, J, through the intervention of the pinion j, to the opposite end of which is attached the pitman K for operating the cutter-bar D. A slotted board, L, hinged to the rear of the platform, is intended to form a guide for the forks f on the fork-band M, the forks projecting through the slot g of the board L, the board being hinged in any suitable way, preferably by simple flat hinges attached to the platform at each end, and held, when turned up, by a suitable locking device, such as indicated at e, Figs. I, II, and III.

When it is intended to cut long grain, such as rye and wheat, the slotted board L may be lowered and extended, as indicated in Fig. I; and for short grain, such as oats, &c., the board L may be turned up, as indicated in dotted lines in Figs. II and III. The board may be lowered and raised by hand, although suitable mechanism might be attached to it in such manner as to enable the driver to raise and lower it without descending to the ground.

The forked band carries the heads of the grain to the binding-platform and runs over sprocket-wheels N. The rod H is secured to shaft-extension of rear wheel, E, and to frame I of guide-wheel O in such manner that the two wheels are compelled to move in opposite directions. The main platform is supported by the drive-wheel E, guide-wheel O, and grain-wheel P, and the inner end of the platform is raised and lowered in the following manner:

The guide-wheel O is mounted in an auxiliary frame, Q, which is pivoted at its front end to the front of frame I by pivot q, whereby the machine may be raised and lowered independently of the wheel O. The auxiliary frame Q, in which wheel O is mounted, is provided with an eye, a, through which passes a cord, R, around a pulley, S, fixed to main platform, thence over a pulley, S', attached to a bridge-piece, T, supported on standards T' of main frame, thence over a pulley, S², whose movement is regulated by a pawl, p, and ratchet-wheel p', both of which are affixed to standards U on bridge-piece T, and said pawl and ratchet-wheel are actuated by a lever, V, operated by the driver. A handle, d² d³, is secured to pulleys S² S⁶, for winding up the cord after the frame is lowered and it is desired to raise it. By releasing the pawl from the ratchet-wheel by means of the levers V V' the cord unwinds from the pulley S² and the machine-front is lowered.

The outer end of the machine is raised and lowered in a similar manner, as follows: The grain-wheel P is mounted in bar W, pivoted at its front end, so that its free or rear end has a vertical motion. An eye, a', is attached to the free end for the passage of a cord, R', which also passes around a pulley, S³, thence over a pulley, S⁴, to pulley S⁵, thence around pulley S⁶, having a pawl and ratchet-wheel on

standards U, similar to and operated in same manner as one already described. By lowering wheels O and P the machine may be converted into a header.

5 Any suitable binding mechanism can be attached to or connected with the grain-platform B.

The forked band M is actuated by sprocket-wheels N, (see Fig. II,) whose diameters are 10 smaller than the diameters of the rollers over which the canvas belts pass, so that the butts of the grain carried by the front belt will move toward the binding-platform faster than the heads carried on the forked band, and the grain 15 delivered on said platform in better shape for binding than if the heads and butts were delivered there at the same time.

Having thus described my invention, what I claim as new, and desire to secure by Letters Patent, is—

20 1. In a harvester, the combination, with a folding slotted board for extending the platform, of a front grain-carrying belt actuated by suitable mechanism, and a rear forked chain or belt the forks of which pass through the 25 slot in the folding-board, substantially as described, and for the purpose set forth.

2. In a harvester, the folding slotted board L for extending the belt-platform, substantially as described.

3. In a harvester, the combination of a rear drive-wheel having a universal-joint-carrying shaft, actuating a cutter-bar through the intervention of suitable mechanism, with a front or guide wheel connected to the drive-wheel by 35 a rod passing under the grain-platform, substantially as described.

4. In a harvester, the combination of a rear drive-wheel the shaft of which is provided with a universal joint with a front guide-wheel 40 mounted in a movable auxiliary frame, the turning movement of the wheels being directed by a rod passing under the platform and secured at one end to the drive-wheel shaft and at the opposite end to the auxiliary platform, 45 as described.

5. In a harvester, an auxiliary frame pivoted to the front platform so as to support the guide-wheel, and having a rod secured thereto and to the shaft of the drive-wheel, substantially as described.

In testimony whereof I affix my signature in presence of two witnesses.

HENRY N. JOHNSTON.
